Primary Examiner — Cathron C Brooks*Assistant Examiner* — Deanna Fluegeman(74) *Attorney, Agent, or Firm* — Jianq Chyun IP Office(57) **CLAIM**

The ornamental design for a display screen with graphic user interface, as shown and described.

DESCRIPTION

FIG. 1 is a front view of a display screen with graphic user interface showing an embodiment of my new design; and, FIG. 2 is a front view of a display screen with graphic user interface showing another embodiment of my new design. The broken line showing of portions of the graphical user interface and the broken line showing of the display screen illustrate unclaimed environment and form no part of the claimed design.

1 Claim, 2 Drawing Sheets**FIG. 1**

FIG. 2
